UNITED STATES PATENT OFFICE.

FREDERICK W. BERNAU, OF DETROIT, MICHIGAN, ASSIGNOR TO ELLIS ADDING TYPE-WRITER COMPANY, OF NEWARK, NEW JERSEY, A CORPORATION OF NEW JERSEY.

SIGNAL-PRINTING MECHANISM.

Application filed January 12, 1925. Serial No. 1,893.

This invention relates to improved signal printing mechanism for adding, listing, bookkeeping, or other machines which mechanically perform calculation.

Signal printers, for machines of this character become necessary for the purpose of distinguishing totals, sub-totals, items which are listed but not added and to distinguish the totals and sub-totals on different accumulators where a plurality of accumulators are provided in the machine, and for other purposes.

The well known "Ellis" printing calculating machine has heretofore operated its signal printer by mechanism cooperatively associated with the accumulating mechanism, or, with the different accumulating mechanisms if more than one accumulating mechanism is used.

Instances of such mechanism appear in patents granted to Halcolm Ellis, No. 1,065,792, June 24, 1913, total signal device, and to me, No. 1,508,267, September 9, 1924, overdraft key locking and indicating mechanism for calculating machines.

My object is to provide, first, improved signal printing mechanism; second, a signal printing mechanism which is manually set by the operation of the respective controlling keys, there being such coordination between the keys and the mechanism which sets the signal printer that when a controlling key is set the signal printer mechanism will be arranged or set so that when printing occurs, on the subsequent operation of the machine, the appropriate signal or symbol corresponding to the set operating key will be printed; third, to provide improved mechanism combined with the signal printing mechanism and the operating or controlling keys in such manner that the different operating or controlling keys will shift the intermediate mechanism to different degrees or extents to permit different extents of movement of the signal printer when the machine is operated; fourth, to provide improved mechanism for controlling the setting of the signal printer by the operating or controlling keys which will serve as a block-out or interlock to prevent the depression of more than one operating key at a time; fifth, to provide improved signal controlling mechanism which will be wholly independent of the accumulator or accumu-

lators of the machine and yet will print an identifying sign or symbol for all items which require identification.

My present improvements are particularly intended for use in connection with the mechanisms and the kind of signal printing arm or sector of the "Ellis" printing calculating machine and for that reason they are shown, and described, in connection with so much of that machine as will afford a clear understanding of the invention and its relationship to the operating keys and printing mechanism thereof, particularly when read in connection with the aforesaid patents and others granted to Halcolm Ellis as follows: No. 1,197,276, September 5, 1916, combined adding machine and typewriter; No. 1,203,863, November 7, 1916, mechanical calculator.

It is to be understood, however, that the present improvements and principles involved therein are not, necessarily, restricted to embodiment in mechanism similar to the "Ellis" machine, as these improvements may be used in other printing calculating machines, and the claims are to be understood as covering any improvements involving the principles of the invention in whatever printing calculating machine they may be employed.

In the accompanying drawings:

Figure 1 is an elevation of the left hand side of the "Ellis" machine showing the improved operating and interlocking slide bar with which the controlling or operating keys cooperate, the various latches and other mechanisms employed in the "Ellis" machine being omitted for the sake of clearness, the parts being in normal position;

Fig. 2 is a similar view, the lower subtotal key being depressed and the slide having been shifted thereby;

Fig. 3 is a side elevation of the signal controlling and operating mechanism on the right hand side of the machine, the parts being in the normal position they assume when the controlling keys and slide are in the normal position shown in Fig. 1;

Fig. 4 is a similar view, the parts being arranged for printing the signal corresponding to the lower sub-total key when the latter has been set as shown in Fig. 2 and after the machine has been started on its cycle of movement;

Fig. 5 is a detail side elevation of certain parts of the mechanism for setting the printing sector;

Fig. 6 is a detail section through the printing sector;

Fig. 7 comprises detail views of the type heads;

Fig. 8 is a detail view of the faces of the symbol types; and

10 Fig. 9 is a detail rear end elevation of the slide, its channel guide, and one of the keys of Fig. 1.

Referring first to Figs. 1 and 2, the top plate through which the keys project appears at K50. The lower part of the machine frame is provided with a channel piece 1, Fig. 9, into which the lower ends of the controlling keys are adapted to slide as they are guided by this channel guide 1 and by 20 the top plate K50.

The usual controlling or operating keys of the "Ellis" machine are shown at K61, K62, K63, K64, K66, K67, K69, being, respectively, the error key, repeat key, total key for 25 lower accumulator, sub-total key for lower accumulator, total key for upper accumulator, sub-total key for upper accumulator and the non-add key.

Reference is to be had to Ellis patents 30 heretofore set forth for latches for holding depressed those keys of this series which it is advantageous, or desirable, to retain in set position until the machine has performed its cycle of operations. The said Ellis patents 35 also disclose various other mechanisms found on the left side of the machine which cooperate with the controlling keys aforesaid and with other mechanisms of the machine. All 40 of these latches, levers, connecting pieces and other mechanisms are omitted for the sake of clearness as the present invention bears no relationship to them.

The different keys are provided with resetting springs for causing them to snap upwardly when they are released.

Slidable in the channel piece 1 is a signal-mechanism-setting, and key-interlocking, bar 2 which is guided by depending projections 2' received in slots in the lower part of the 50 guide 1.

The slide bar 2 is provided with notches 100, 101, 102, 103, 104, to receive the lower ends of the stems of keys K63, K64, K66, K67, K69, respectively, after these keys are 55 depressed. For instance, in Fig. 2 the lower sub-total key K64 has been depressed and it will be seen that its lower end has entered the notch 101. When any one of the operating keys has thus been depressed, the resulting engagement of the lower end of the key stem with the notch for that stem, positively locks the slide bar 2 so that it is impossible to depress any of the remaining operating keys and thus an interlock is provided between the keys.

The error and repeat keys K61, K62, do not cooperate with the slide bar 2.

To enable the slide bar 2 to be shifted when one of the keys K63, K64, K66, K67, K69, is depressed, said bar is provided with 70 a series of cam surfaces 105, 106, 107, 108, 109, which are arranged, respectively, immediately under the lower ends of the key stems when the parts are in normal position as shown in Fig. 1. Consequently, on the depression of any key of the series K63, K64, K66, K67, K69, there will be exerted a camming action between the depressed key and the cam or bevel surfaces 105, 106, etc., whereby the slide bar 2 will be moved toward the left, Fig. 1, until the lower end of the key stem registers with the notch 100, 101, etc.; thereupon, the key holds the bar 2 in a position which blocks the remaining key stems so that they cannot be depressed. 85

The cam surfaces 105, 106, 107, 108, 109, are arranged vernier fashion, that is, of different angles and relationships to the lower ends of the key stems so that depression of any one of the controlling keys will result in 90 a different extent of travel of the bar 2 than will be obtained by depression of any other key of the series. As shown, depression of the key K63 will move the bar 2 to the left a lesser distance than will be accomplished 95 when key K64 is depressed. Similarly, depression of key K66 will move the bar 2 a greater distance than it will be moved by key K64, and so on.

This principle is utilized to set a vernier 100 slide 12, Figs. 3 and 4, toward the right, in said figures, different distances so that the lug 50 on a pivoted controlling arm 14 may rise to properly set the signal printing sector P54 to adapt said sector to print a 105 symbol corresponding to the depressed controlling key, when the machine is subsequently put through its cycle of operations as shown, for instance, in Fig. 4.

In Fig. 4 the vernier slide has been set 110 by the depression of key K64, as shown in Fig. 2, such a distance that when the paper feed lever P74 moves downwardly from the normal position of Fig. 3 to the position of Fig. 4 when the machine is operated, the 115 controlling arm 14 will be pulled upwardly by spring 16 until arrested by the proper step or shoulder of the vernier arrangement on slide 12 to position the printing sector P54 so that a symbol corresponding to the 120 function of the machine controlled by key K64 will be printed.

As shown in Fig. 2, the symbol adopted to indicate that the printed item identified is a sub-total taken from the lower accumulator, such symbol being S.

The operative connections between the slide bar 2 and the vernier, or portable, slide 12 are as follows: The bar 2 is provided with an upwardly extending arm 2''. A shaft 130

L1 which is journaled in bearings F of the main frame of the machine, is provided at its left hand end with a crank 5. Pivoted to the crank 5 on a pin 6 is a connecting link 4 which is also pivoted at 3 to the arm 2''. On the right hand end of shaft L1 is a crank 7. A spring 150 connected to the bearing F and to the hub of crank 7 tends to turn the shaft L1 to normally cause the 10 slide bar 2 to be held in the position shown in Fig. 1 with its lug 2''' engaged with the left hand end of the channel member 1. The spring 150 also holds the variable vernier slide 12 normally in the position shown in Fig. 3. To accomplish this purpose the 15 crank 7 is provided with a pin 8 which is received in a slot at the lower end of a bell crank lever 9 which is pivoted at 10 to the side frame 160 of the printing section. The 20 upper end of bell crank lever 9 is pivoted at 11 to the forward end of the variable vernier slide 12. The vernier slide 12 has a slot 17 in its rear part which loosely receives a pin 13 carried by the side frame 160, thus supporting the slide 12 so that it 25 may be moved rearwardly as shown in Fig. 4.

The slide 12 has a series of steps or shoulders 120, 121, 122, 123, 124, which, according to the setting of the slide 12 rearwardly, selectively determine how far the lug 50 of the controlling arm 14 will be permitted to rise when the machine is put through its cycle of operations. As previously described, the setting of the slide 12 is dependent upon the operation of the controlling keys K63, K64, etc. For instance, in Fig. 4 the slide 12 has been set, by the depression of key K64 and, hence, when the machine is operated the controlling arm 14 will rise, until arrested by shoulder 122, when the right hand end of paper feed lever P74 moves downwardly.

Normally, the paper feed lever P74 of the "Ellis" machine is in the position shown in Fig. 3. Therefore, when a controlling key is set, for instance key K64, while the shaft L1 is rocked against the action of spring 150 and the bell crank lever 9 is 50 turned to move the slide 12 rearwardly to the position shown in Fig. 4, nevertheless as the paper feed lever P74 is not shifted until at a certain time when the machine is put through its cycle of operations, the restoring fork 20 which is pivoted at 21 to the controlling arm 14 is blocked and, hence, the spring 16 cannot turn the controlling arm 14 on its pivot 15 but when the paper feed lever P74 moves downwardly as shown 55 in Fig. 4, the pin P14 carried by the paper feed lever is moved in the slotted end of the restoring fork 20 so that the said fork is freed and the spring 16 may then turn the controlling arm 14 as far as will be permitted before the lug 50 will be arrested by

one of the steps or shoulders of the series 120, 121, etc.

When the machine is set to perform addition, the operating keys are as shown in Fig. 1 and the slide 12 is arranged as shown in Fig. 3. This results in the shoulder 120, 70 by its engagement with the lug 50, holding the controlling arm 14 in its retracted position. Consequently the printing sector P54 is held in a non-print position and a releasing pawl 17 which is pivoted to the controlling arm 14 at 18, is held in its retracted position. The releasing pawl 17 is most clearly illustrated in Fig. 5, being pulled upwardly by a spring 19 so that the left 80 hand end of the releasing pawl 17 bears against the release dog 63P whose purpose is explained in the "Ellis" patents.

As explained in the "Ellis" patents heretofore referred to, the printing arm 54P of the signal printer carries the printing sector P54 of the signal printer which is pivoted thereto at P10P. The signal printer sector P54 is set by the link 22 which is pivoted thereto at P10 and pivoted to the controlling arm 14 at 140 so that the printing sector P54 will be set according to the setting of the controlling arm 14.

When the machine is put through its cycle of operations to print the item, whatever it may be, the releasing pawl 17 moves to the position shown in Fig. 4, thereby causing the release dog 63P to move through an angle of about ten degrees on its pivot. This will cause certain mechanism to become 100 disengaged from the printing arm 54P. The purpose of making the controlling arm 14 and the releasing pawl 17 flexible in relation to each other by the use of the spring 19, is to permit the controlling arm 14 to 105 continue its upward movement, according to the setting of the slide 12, after the releasing pawl 17 has moved sufficiently to cause the release dog 63P to accomplish the release of the printing arm 54P. Were there 110 no flexible connection between the pawl 17 and the arm 14, the arm 14 could not continue its movement to the desired extent, beyond a certain point, under the control of spring 16.

The signal printing sector may be made as a single stamping of the cross sectional shape shown in Fig. 6 and of the outline appearing in Figs. 3 and 4. The sector is provided with fingers 170 of the necessary 120 number to carry the printing type appearing in Figs. 7 and 8, according to the number of symbols desired for the controlling keys K63, K64, etc., which are used on the machine. The fingers 170 are provided with 125 bowed parts 171.

By using fingers such as shown and described, it is an easy matter to apply individual symbol type thereto and to aline them and arrange them so that clear impres- 130

sions on the paper on the platen P will result. Beside this, the use of the bowed parts 171 affords a cushioning action when the impression is made on the paper.

5 Any desired symbols may be used, those shown in Fig. 8 being at present preferred. These symbols are in the form of type 180 which are carried by heads or caps P55 of split construction which straddle the fingers 10 170 and are soldered or otherwise suitably secured to them.

By providing separate fingers 170 on the signal printing sector, any desired series of combination of symbol type may be provided, thus avoiding the necessity of using a series of symbol type cast en bloc, as previously proposed.

I claim:

1. In a calculating machine, the combination with a signal indicator adapted to be set to different positions, of a plurality of operating keys adapted for controlling different functions of the machine, a combined actuator and key interlock which is common 20 to the operating keys and adapted to be set to different degrees or extents by them, when said keys are set, said actuator locking the unset keys to prevent operation thereof after one of said keys has been set 25 and mechanism interposed between said actuator and the signal indicator by which the signal indicator is adapted to be set in a different position.

2. In a calculating machine, the combination with a plurality of operating keys 30 adapted for controlling different functions 35

of the machine, of a slide having notches and cams leading to said notches, arranged of vernier fashion and adapted for cooperation with aforesaid keys, whereby when one 40 of said keys is operated, the action of the operated key on one of the cams moves said slide to a position in which it will prevent operation of the remaining keys, a signal printer, and mechanism interposed between 45 the signal printer and the slide by which the setting and locking of said signal printer is predetermined by the position of the slide as set by the operation of a key.

3. In a calculating machine, the combination with a plurality of operating keys adapted for controlling different functions of the machine, of a slide having notches and cams leading to said notches, arranged of vernier fashion and adapted for cooperation with aforesaid keys, whereby when one 50 of said keys is operated, the action of the operated key on one of the cams moves said slide to a position in which it will prevent operation of the remaining keys, a slide having 55 a plurality of stops, operative connections between said last named slide and the vernier slide, a signal printer, and mechanism brought into action when the machine is put through its cycle of operations which determines the setting of the signal printer by the arrest of said mechanism by one of said stops, determined by the setting of said stop slide.

In testimony whereof I affix my signature.

FREDERICK W. BERNAU.
